Term of patent 14 years

U.S. Cl. D90—20
Int. Cl. D12—14

Fig. 1

FIG. 1 is a perspective view of a tire embodying my new design, it being understood that the full-line portion is repeated throughout the circumference of the tire, shown by means of broken lines;

FIG. 2 is an enlarged fragmentary side elevational view of the full-line ornamental portion of the sidewall configuration shown in FIG. 1;

FIG. 3 is an enlarged fragmentary plan view of the tread portion of the tire shown in FIG. 1;

FIG. 4 is a sectional view taken substantially on the plane indicated by line IV—IV of FIG. 3; and

FIG. 5 is a detailed sectional view taken substantially on the plane indicated by line V—V of FIG. 2.

The dominant features of my design reside in those portions shown in full lines in the drawings.

I claim:

The ornamental design for a tire, substantially as shown and described.
